BLOCK FOR BUILDING

Thomas J. Stoy, P.O. Box 58, Bigler Road, Clearfield, Pa.

Filed June 10, 1963, Ser. No. 75,276

Term of patent 7 years

(Cl. D18—2)

FIG. 1

FIG. 2

FIG. 3

FIG. 4

FIG. 1 is a perspective three-dimensional view of the block for building of this invention;

FIG. 2 is a front elevation of the block for building of FIG. 1;

FIG. 3 is a side elevation of the block for building of FIG. 1; and

FIG. 4 is a bottom view of the block for building of FIG. 1.

I claim:

The ornamental design for a block for building, as shown.
